UNITED STATES PATENT OFFICE.

ALLISON M. STICKNEY, OF MEDFORD, ASSIGNOR TO THE WELLMAN SOLE CUTTING MACHINE COMPANY, OF BOSTON, MASSACHUSETTS.

SOLE-CUTTING MACHINE.

SPECIFICATION forming part of Letters Patent No. 443,123, dated December 23, 1890.

Application filed November 18, 1889. Serial No. 330,776. (No model.)

To all whom it may concern:

Be it known that I, ALLISON MORRIS STICKNEY, of Medford, in the county of Middlesex and State of Massachusetts, have invented an

5 Improved Machine for Cutting Soles and other Forms, of which the following is a specification, reference being had to the accompanying drawings, in which—

Figure 1 is a side elevation, and Fig. 2 a 10 front elevation, of one of my improved machines. Fig. 3 is a plan, and Fig. 4 an elevation, of the knife-block carrier. Fig. 5 is an elevation of the rack, the forms, the knife-block, and a portion of its carrier. Fig. 6 is 15 a section on line 6 6 of Fig. 5. Fig. 7 is a section on line 7 7 of Fig. 6. Fig. 8 is a plan of the upper part of the knife-block detached, and Fig. 9 one of the rollers. Fig. 10 is a 20 plan, partly in section, of the rack; and Fig. 11, a bottom plan of the rack with the upper part of the knife-block, also shown in bottom plan; Fig. 12, a section on line 12 12 of Fig. 11.

My machine is an improvement on that 25 patented to Willard F. Wellman by Patent No. 391,287, dated October 16, 1888, and is like that machine, except as hereinafter described. Its main purpose is the cutting of soles with beveled edges; but, as will be clear, it is adapted for cutting vamps and a large 30 variety of other forms either with beveled or square edges.

My machine consists of a knife-block in two parts, which is traveled about a form which corresponds generally in outline to the 35 outline of the form to be cut, one part of the knife-block being guided by that form, while the other part, which carries the knife, is guided by a second form which corresponds in outline with the form to be cut. This combination of a knife-block in two parts with 40 two guides, one guiding one part of the knife-block in a closed or endless path and the other part in a special path, is not broadly new with me; but nevertheless the main feature of my invention is the combination of a 45 knife-block in two parts with two forms and with means for traveling the knife-block about these forms, for in all prior machines for doing this work by means of a general guide 50 for one part of the knife-block and a special guide or form for that part of the knife-block

to which the knife was secured the general guide served simply to give the knife-block a motion in a closed path, and its curves did not correspond with the curves of the article 55 to be cut—that is to say, the general guide did not have inward curves and outward curves corresponding to the inward and outward curves of the article to be cut, and was not in substance a form, but merely a general 60 guide. The practical difference between my combination and the prior one is that by mine the knife-block as a whole is not only guided in a closed path, but the line 12 12 in Fig. 11 (which is kept always substantially at right 65 angles with the edge of the form, no matter at what part of the form the knife-block may be) is always a radius of the curve at any part of the form, and in order that the bevel cut by the knife on the edge of the article 70 may be uniform throughout it is essential that both parts of the knife-block shall be controlled by forms which are alike so far as corresponding with both inward and outward curves of the article to be cut.

75 So far as I know I am the first to obtain the uniformity and degree of bevel required by any means; and the chief feature of my invention is the solution of this problem.

I have found it not only necessary to use 80 two forms, each of which corresponds with both the inward and the outward curves of the article to be cut, as above described, but also to separate those forms, as shown in Fig. 5, in order that the size of the article may be 85 smaller than the form by which the main part of the knife-block is guided, for it is of very great practical importance that this form be made of an intermediate size in order that one of these forms shall serve for all the sizes 90 to be cut. This separation of the two forms is also essential in order that the required degree of bevel may be obtained, as will be clear from Fig. 5, in which the knife is shown in full lines cutting one size and in dotted lines 95 cutting a larger and a smaller size, all with the same bevel, for the upper form is so far above the lower that the knife may be arranged with any desired bevel.

The knife-block carrier is substantially the 100 same as in the Wellman patent, the only difference being that I prefer gears rather than

belts and pulleys, as the gears are positive, while the belts are likely to slip and are otherwise inferior in my opinion. In the preferred construction the knife-block carrier is supported by shaft 1 and is made up of an arm 2, hubs 3 of which are on shaft 1 and supported by a collar 4 thereon. Arm 2 has hubs 5, through which shaft 6 passes, and on this shaft an arm 7, having hubs 8 to receive shaft 10, which carries the knife-block. On shaft 1 a gear 11 is mounted, and this gear meshes with a gear 12, mounted on arm 2 intermediate gear 11 and gear 13 on shaft 6, which also carries a gear 14, which meshes with a gear 15, mounted on arm 7 intermediate gear 14 and gear 17 on the shaft 10, carrying the knife-block. Motion is given shaft 1 by any suitable means, as by belt 16 and pulley 17, as will be plain to all skilled in the art.

The table is the same as that of the Wellman patent, except that it is lifted by four cams instead of two. The parts not lettered are either the same or differ merely in details of construction from the corresponding parts of the Wellman machine. The form A, for controlling the main part b of the knife-block B, is shown as a rib projecting from the rack-plate, by which that knife-block carrier is caused to travel the knife-block B about the forms A and A' much as in the Wellman machine. The form A' is a pattern-plate, preferably of sheet metal, and is not only of the shape of the article to be cut, but of nearly the same size. The knife-block B consists of two parts b b', (the part b being supported by the outer shaft of the knife-block carrier, as in the Wellman machine,) the part b' being movable with relation to part b, so that the knife may follow the form A', and the part b', as shown, is a slide supported by ways which are fast to part b, the part b' being thrown forward in its ways by the chain and pulley b² b³, the sleeve on pulley b³ being attached to one end of a spiral spring b⁴, (see Fig. 7,) whose other end is fast to its box b⁵, which is held from revolving.

The operation is as follows: The material to be cut is placed upon the table and clamped between the table and the form A' by depressing the cam-treadle, as in the Wellman Machine. The machine is then started, the rotation of the gears of the knife-block carrier causing the pinion, (see Figs. 1 and 5,) which is engaged with the rack just above form A, to compel the knife-block to travel

about the forms A and A'. The form A guides and controls the part b of the knife-block B, for the roller 1 of part b (see Figs. 8, 60 11, and 12) is on one side of the rib which constitutes form A, while the rollers 2 and 3 are on the other side, so that not only is the path of part b controlled by form A, but also the relation of part b to form A, the central line of part b being always kept at substantially a right angle to that part of form between the rollers 2 and 3. The part b' of knife-block B is controlled by the form A' as well as (indirectly through part b) by form A, and thereby compelled to cut an article which corresponds almost exactly with form A'; but the edge of the article can be given any desired bevel by setting the knife on a slant, and this bevel will be made uniform by the joint action of 75 the forms A and A' on the parts b and b' of the knife-block B. The form A, being intermediate, will suffice for any size of sole of that style; but the form A' is changed for each size by detaching it from the post 1 and attaching another of the desired size. Slight variations of style may also be cut without changing form A; but in practice it is better to change form A for any change of style. As shown in the drawings, the form A is in 80 one piece with the rack, and consequently the rack must also be changed whenever form A is changed. This is on the whole desirable, as making form A separate from the rack will require undesirable changes in the 85 machine.

What I claim as my invention is—

1. In a machine for cutting soles and the like, the two forms A and A', each corresponding in outline to the outline of the article to be cut, the knife-carrier B, composed of two parts b and b', one controlled by the form A and the other by the form A', and mechanism, substantially such as is described, for traveling the knife-block about the forms, all 90 combined and operating substantially as described.

2. In a machine for cutting soles and the like, the combination of form A, posts 1 and 6, form A', and knife-block B, composed of 100 two parts b b', the part b' carrying the knife and extending under form A and over form A', and intermediate connections between the posts and the knife-block, substantially as and for the purpose set forth.

ALLISON M. STICKNEY.
